UNITED STATES PATENT OFFICE.

THOMAS BURTON MILLER, OF SEATTLE, WASHINGTON, ASSIGNOR OF ONE-HALF TO
SMITH CANNERY MACHINES COMPANY, OF SEATTLE, WASHINGTON, A CORPORA-
TION OF WASHINGTON.

INTERFERENCE-PREVENTER.

1,127,368.

Specification of Letters Patent.

Patented Feb. 2, 1915.

Application filed January 6, 1913. Serial No. 740,385.

To all whom it may concern:

Be it known that I, THOMAS BURTON MILLER, citizen of the United States, residing at Seattle, in the county of King and 5 State of Washington, have invented a certain new and useful Improvement in Interference-Preventers, of which the following is a specification.

My invention relates to improvements in 10 devices known as interference preventers that may be connected in circuits with a receiving apparatus of a wireless telegraph station whereby radiant Hertzian waves, representing signals, which may emanate 15 from a desired particular one of different distant wireless telegraph stations that are generating and sending out such waves, may be perceived exclusively and interpreted by a telegraph operator; and the object of my 20 invention is to provide wireless telegraph stations with circuits and apparatus associated therewith which apparatus shall be adapted to be adjusted to be acted upon by the weak electric waves arriving from a far 25 distant station, or by the weak waves of a nearer station of small power, whereby such waves may be perceived and interpreted by an operator without interference or interruption by stronger electrical waves which 30 at the same time may be emanating from a nearby or from a more powerful distant station.

I attain this object by electrical circuits and devices connected therewith which are 35 illustrated in the accompanying drawings, wherein—

Figure 1 is a diagrammatic illustration of 40 circuits and different devices connected therein which circuits and devices comprise the essential features of my invention, while Fig. 2 illustrates, by a view in longitudinal vertical section, three electrical helices and by a view in side elevation it shows a magnetizable core disposed within said helices, 45 which helices and core form a part of my invention.

Like reference numerals indicate like parts throughout the drawings.

Referring to Fig. 1 of the drawings 3 is 50 the primary winding of an air-core transformer which is provided with two separate secondary windings 4 and 5.

The lower terminal of the primary winding 3 is indicated as being connected with

the earth 6 while its upper terminal may 55 extend to connect with the antenna of a wireless telegraph station. The secondary winding 4 has its upper terminal connected by a conducting wire 7 with one terminal of a rectifying detector 8 the other terminal of said detector 8 being connected with one terminal of an electrical helix 10 by means of a conducting wire 9 the other terminal of said electrical helix 10 being connected by a conducting wire 11 with the 60 lower terminal of said secondary winding 4 while an electrical condenser 12 is connected by one of its terminals to the conducting wire 11 and its other terminal to the conducting wire 9.

Similarly the upper terminal of said secondary winding 5 is connected by conductor 13 with one terminal of another rectifying detector 14 whose other terminal is connected by conductor 15 with one terminal of another electrical helix 16 whose other terminal is connected by a conductor 17 with the lower terminal of said secondary winding 5, there being another electrical condenser 18 which is connected with one 80 of its terminals to conductor 17 and its other terminal to conductor 15.

Within the helices 10 and 16 is movably disposed a magnetizable core 19 whose central portion normally is surrounded by a longitudinally movable helix 20 which may be referred to as the secondary helix of the core 19 while the helix 10 and the helix 16 may act as the primary coils of said core 19.

The direction of winding of the convolutions of wire of the helices 10 and 16 respectively is such as to cause them to have the tendency to oppose each other in their inductive influence on the core 19 and the helix 20 when both are subjected to the action of like electrical waves.

In practice I have found it preferable to so construct and dispose in suitable supporting devices, not shown, each of the helices 10, 16, and 20 and the core 19, that each independently may be moved horizontally with relation to the others, whereby the helix 20, of larger internal diameter, may be moved longitudinally in a direction toward either end of the core 19, to surround any desired portion of the helix 10 or the helix 16 as required; or either or both of the helices 10 and 16 may be moved longitudi-

dinally to any position with relation to the core 19 and the helix 20, and thus the core 19 and the helices 10, 16 and 20 may be moved to positions with relation to each other as desired to cause inductive influence of either one of the helices 10 and 16 upon the helix 20 to be neutralized by the other of said helices 10 and 16 whether such inductive influence be direct or through the magnetizable core 19.

In Fig. 2 I have shown by view in longitudinal vertical section one form of the helices 20, 10, and 16 as disposed on a core 19 in a position wherein if electrical waves 15 of a given strength and of like character, be caused to flow through helices 10 and 16, then no inductive influence could affect the helix 20, since the action of helix 10 would neutralize or counteract the action of helix 20 16, but manifestly if the helix 20, the helix 10, the helix 16 or the core 19 alone be moved, then, in such case, the action on the helix 20 by one of the helices 10 and 16 would not wholly be neutralized or counteracted.

In Fig. 1 I have shown an operator's receiving telephone 21 connected by wires 22 and 23 in circuit with helix 20 which telephone 21 obviously may enable an operator 30 to perceive signals due to waves induced in said helix 20 by resultant inductive action of helices 10 and 16.

The mode of operation of my invention when embodied in the apparatus in circuits 25 represented by Fig. 1 is as follows: Electrical waves which emanate from each of different distant wireless stations, to represent intelligible signals, find passageway through an antenna, not shown, to the 40 upper terminal of the primary winding 3 of an air-core transformer and through said primary winding 3 to the earth 6, in a manner well known, whereby corresponding waves are inductively impressed 45 in each of the two secondary windings 4 and 5, of said air-core transformer, such waves generated in the secondary winding 4 having a tendency to flow through wire 7 to and through the rectifying detector 8 thence through conductor 9 to and through the helix 10 and therefrom through the conductor 11 back to the secondary winding 4; and such waves as are generated in said secondary winding 4 are 50 alternating in polarity, but to the extent of its capability the rectifying detector 8 permits the passage through it of waves only of the same polarity, thus waves of such same polarity, comprising what might be 55 described as an intermittent direct current, reaches and passes through the helix 10 by the way of the conductor 9 while waves of different polarity find a passageway of little or no resistance through the condenser 12; 60 thus the helix 10 is subjected only to waves

of one like polarity. Likewise the waves generated in secondary winding 5, passing through conductor 13 to detector 14 to be subjected to the rectifying properties of said detector 14, reach and pass through the 70 helix 16 in the form of direct intermittent currents thence back to said secondary winding 5 through the conductor 17, any unrectified portion of said waves finding a short path through condenser 18.

Thus, with helices 10 and 16 wound in opposite directions, and disposed symmetrically with relation to the helix 20 and the core 19, and with detectors 8 and 14 being exactly alike in character and adjustment, 80 any waves traversing said helices 10 and 16 could not affect the helix 20 to make perceptible signals in the receiving telephone 21 but if one distant station be sending out strong waves while another station is sending out weak waves and if it be desired to have the receiving telephone 21 affected only by the weak waves of such other station then it would be necessary to adjust one of the two detectors, say detector 8, to rectify 90 strong waves only and then to adjust detector 14 to rectify the weak waves with maximum effect, whereupon the helix 20 should be moved away from the helix 10 toward the helix 16 in the direction indicated 95 by the arrow in Fig. 1, until the strong waves in said helix 10 affect the helix 20 only to counteract accurately the effect of strong waves in the helix 16, whereby the coil 20 will then be affected only by the 100 weak waves of like polarity that have been rectified by detector 14 which weak waves will perceptibly affect the receiving telephone 21.

A movement of the core 19 toward the 105 right or a movement of the helix 10 toward the left for a required distance may also cause or assist in causing the same result; and obviously the positions of the helices 10, 16 and 20 may be changed to select the waves 110 from any one of the stations irrespective of the strength of such waves as compared to the strength of waves of other stations, provided, of course, all such stations be within the range of the apparatus of my invention. 115

Manifestly, devices may be applied to the primary winding 3 or to the secondary windings 4 and 5 for changing the number of active convolutions in circuit and other minor modifications may be made without 120 departing from the spirit of my invention.

What I claim is:

1. In a receiving apparatus of a wireless telegraph station, the combination with a transformer having a primary helix adapted 125 for connecting one of its terminals to the earth and its other terminal to the antenna of a wireless telegraph station and having two secondary helices, of two separate oscillating circuits each of which oscillating cir-

- cuits includes one of said secondary helices, two detectors one of which is connected in each of said oscillating circuits in series with said secondary helix therein, 5 and having two secondary helices, of another transformer having two primary helices and one secondary helix, each of said primary helices being disposed in electrical connection with a different one of said secondary helices of said first named transformer, two detectors each of which is disposed in electrical connection with a different one of said two secondary helices of said first named transformer, and a receiving instrument disposed in electrical connection with the secondary of said second named transformer. 25
- 10 a condenser connected in each of said oscillating circuits in series with said detector and said secondary helix therein, two primary helices each of which helices is connected with a different one of said oscillating circuits in parallel with the said condenser therein, a magnetizable core inductively and movably associated with both of said primary helices, a secondary helix movably and inductively associated with said magnetizable core and both of said primary helices and a translating device connected with said secondary helix. 30
- 15 2. In a receiving apparatus of a wireless telegraph station, the combination with a transformer having a primary helix that is adapted to be connected with an antenna, 35

In witness whereof, I, hereunto subscribe my name this 27th day of December A. D., 1912.

THOMAS BURTON MILLER.
